By his Attorney, *Alfred Karp*

UNITED STATES PATENT OFFICE.

BYRON B. GOLDSMITH, OF NEW YORK, N. Y.

MOUNTING FOR RUBBER ERASERS.

Application filed November 13, 1924. Serial No. 749,793.

The present invention relates to an improved mounting for rubber erasers whether used as independent articles or secured to the end of a pencil or pencil point protector, as is common in this art. My improved device comprises, a socket in combination with a clamp directly applied to the eraser itself and adapted to fit into said socket.

Clamps have been used hitherto for this purpose, but there has always been some difficulty in pushing the clamp in a satisfactory manner into the socket, due to the slight differences in the thicknesses of different erasers. Moreover, where flat erasers have been used, it has been necessary to use flat sockets.

One advantage of my present invention is that the construction of clamp and socket is such as to make it easy to unite them, despite the variations in thickness of the erasers met with in practical manufacture. Another advantage is that my mounting does not employ a flat socket, and is therefore adapted to tasteful and presentable use on the end of a pencil point protector.

The invention is illustrated in a preferred form in the accompanying drawing wherein Figure 1 is a front elevation of my mounting on a pencil, Figure 2 shows the same on a larger scale in the edge view with the clamp and socket separated, Figure 3 is a side view of the clamp alone, shown in open position, and Figure 4 is a front elevation of my mounting on a pencil point protector.

My improved clamp comprises preferably a piece of sheet metal struck up to form two similar upstanding rounded sides 10 each having serrated edges facing the similar edges of the other, and a strip 11 uniting these sides at the bottom. This clamp is squeezed together against the middle of the sides of a flat eraser 12, as shown clearly

in Figure 2. The opposite edges of the eraser extend beyond the clamp.

The socket is also preferably formed from sheet metal, and comprises oppositely facing rounded parts 13 which fit the rounded sides 10 of the clamp; these sides being joined by extensions 14 on each side of substantially rectangular form, to receive those parts of the eraser that extend on each side beyond the clamp sides 10.

Where the mounting is used on a pencil 15, it comprises further an extension 16 adapted to be fitted onto the pencil.

If desired this whole socket may be an integral part of a well known sheet metal point protector 17, as shown in Figure 4.

As clearly shown in Figure 2, the sides of the clamp 10, when applied to the eraser are slightly tapered, being narrower at the bottom than at the top, and the flat sided extensions on the socket lend a certain amount of resilience to the same. Hence, whatever are the small variations in thickness between different erasers 12, the combined eraser and clamp can always be easily forced into place in the socket. It will, of course, be understood that the flat sided extensions 14 should always be made wide enough to accommodate the thickest erasers to be expected.

What I claim is—

A pencil eraser comprising a socket having a wider middle portion and narrower side portions, a separable tapering clamp adapted to be closed by forcing into the wider portion of the socket, and a rubber eraser wide enough to extend across the entire socket and fitting the side portions thereof while in the grip of said clamp.

In testimony whereof I have hereto set my hand on this 3rd day of November 1924.

BYRON B. GOLDSMITH.
